United States Patent Office

Des. 193,023
Patented June 12, 1962

193,023

METER BOX

Robert L. Whitman, Jackson, Mich., assignor to Handley Industries, Inc., Jackson, Mich., a corporation of Michigan

Filed Apr. 28, 1961, Ser. No. 64,946

Term of patent 14 years

(Cl. D52—6)

FIG. 1

FIG. 2

FIG. 3

FIG. 4

FIG. 1 is a front perspective view of a meter box, showing my new design;

FIG. 2 is a front elevational view;

FIG. 3 is a top plan view; and

FIG. 4 is a side elevational view thereof taken from the right of FIG. 2.

The bottom of the box is open and the box is hollow and conforms in shape to the outer configuration shown.

I claim:

The ornamental design for a meter box, as shown and described.
